CLAIM

The ornamental design for a bottle container, as shown and described.

DESCRIPTION

FIG. 1 is a front perspective view of a bottle container showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof; and,

FIG. 8 is another perspective view thereof, with the lid engaged.

The broken lines in the drawings depict environmental subject matter, specifically a lid in FIG. 8, and forms no part of the claimed design.
